Des. 196,681
Patented Oct. 22, 1963

196,681

CONTACT LENS CASE

Robert E. Middleton, 5865 E. Alexander Ave.,
Englewood, Colo.

Filed Dec. 3, 1962, Ser. No. 72,688

Term of patent 14 years

(Cl. D57—1)

FIGURE 1

FIGURE 2

FIGURE 3

FIGURE 4

FIGURE 5

FIGURE 1 is a perspective view of a contact lens case showing my new design;

FIGURE 2 is an end view thereof taken from the left side of the showing in FIGURE 1;

FIGURE 3 is a side elevational view of the contact lens case of FIGURE 1;

FIGURE 4 is an end view of the contact lens case taken from the right side of the showing of FIGURE 1; and

FIGURE 5 is a top view of the contact lens case of FIGURE 1.

The dominant features of my design reside in the portions shown in full lines.

I claim:

The ornamental design for a contact lens case, as shown and described.
